(57) **CLAIM**

The ornamental design for a cooking rack for ribs, chicken wings, chicken legs, or the like, as shown and described.

DESCRIPTION

FIG. 1 is a top perspective view of a cooking rack for ribs, chicken wings, chicken legs, or the like showing my new

design, wherein the cooking rack for ribs, chicken wings, chicken legs, or the like is in a first orientation in which the cooking rack for ribs, chicken wings, chicken legs, or the like may be used to support meat, such as slabs of ribs, during grilling;

FIG. 2 is a top plan view of the cooking rack for ribs, chicken wings, chicken legs, or the like in the first orientation;

FIG. 3 is a bottom plan view of the cooking rack for ribs, chicken wings, chicken legs, or the like in the first orientation;

FIG. 4 is a right elevation view of the cooking rack for ribs, chicken wings, chicken legs, or the like in the first orientation;

FIG. 5 is a left elevation view of the cooking rack for ribs, chicken wings, chicken legs, or the like in the first orientation;

FIG. 6 is a front elevation view of the cooking rack for ribs, chicken wings, chicken legs, or the like in the first orientation;

FIG. 7 is a rear elevation view of the cooking rack for ribs, chicken wings, chicken legs, or the like in the first orientation;

FIG. 8 is a top perspective view of the cooking rack for ribs, chicken wings, chicken legs, or the like in a second orientation in which the cooking rack for ribs, chicken wings, chicken legs, or the like may be used to support meat, such as chicken wings and/or chicken legs, during grilling;

FIG. 9 is a top plan view of the cooking rack for ribs, chicken wings, chicken legs, or the like in the second orientation;

FIG. 10 is a bottom plan view of the cooking rack for ribs, chicken wings, chicken legs, or the like in the second orientation;

FIG. 11 is a right elevation view of the cooking rack for ribs, chicken wings, chicken legs, or the like in the second orientation;

FIG. 12 is a left elevation view of the cooking rack for ribs, chicken wings, chicken legs, or the like in the second orientation;

FIG. 13 is a front elevation view of the cooking rack for ribs, chicken wings, chicken legs, or the like in the second orientation; and,

(Continued)

FIG. 14 is a rear elevation view of the cooking rack for ribs, chicken wings, chicken legs, or the like in the second orientation.
